Primary Examiner — Jack Reickel*Assistant Examiner* — Bobby W Jones, II(74) *Attorney, Agent, or Firm* — Foley & Lardner LLP(57) **CLAIM**

The ornamental design for an electrostatic sprayer, as shown and described.

DESCRIPTION

FIG. 1 is a side perspective view of the electrostatic sprayer of the present invention.

FIG. 2 is a front plan view of the sprayer of FIG. 1.

FIG. 3 is a back plan view of the sprayer of FIG. 1.

FIG. 4 is a right side view of the sprayer of FIG. 1.

FIG. 5 is a left side view of the sprayer of FIG. 1.

FIG. 6 is a top side view of the sprayer of FIG. 1; and, FIG. 7 is a bottom side view of the sprayer of FIG. 1.

The broken line showing of an electrostatic sprayer is for the purpose of illustrating portions of the article and forms no part of the claimed design.

The drawings are shown with a symbolic break in length, the appearance of any portion of the article between the break lines forms no part of the claimed design.

1 Claim, 5 Drawing Sheets
